UNITED STATES PATENT OFFICE.

JOHN ULMER RUSS, OF DERBY, CONNECTICUT, ASSIGNOR TO ROBERT N. BASSETT COMPANY, INCORPORATED, OF SHELTON, CONNECTICUT, A CORPORATION OF CONNECTICUT.

BUCKLE.

1,337,965.

Specification of Letters Patent. Patented Apr. 20, 1920.

Application filed November 22, 1918, Serial No. 263,665. Renewed February 18, 1920. Serial No. 359,539.

To all whom it may concern:

Be it known that I, JOHN U. RUSS, a citizen of the United States, residing at Derby, in the county of New Haven and State of Connecticut, have invented a certain new and useful Improvement in Buckles, of which the following is a specification.

My invention relates to buckles for running webbing of the kind generally used on hose supporters, suspenders, belts and the like, and its object is to construct an economical, durable and attractive buckle.

My buckle belongs to the class generally known as slide buckles wherein the moving portion of the webbing is threaded through two or more slots and its extremity secured to the attaching member between the slots. Buckles of this style are well known in the art and the particular kind to which mine relates generally consists of a rectangular frame provided with a web-attaching bar or member disposed across the middle of the frame in a manner so as to be slideable up and down upon the side members of the frame between the upper and lower slots. My invention consists in constructing such a buckle so that the end of the webbing may be attached thereto by a swaging operation and the sliding member will operate in such a manner as to more effectively grip the moving, or adjustable portion, than in the present style of buckle.

In order that my invention may be better understood by those skilled in the art I have embodied the same in the new and improved buckle set forth in the following description and accompanying drawings in which like reference characters refer to corresponding parts.

40 In the drawings:

Figure 1 is a front view of my buckle strung with webbing a portion of the webbing being shown broken away.

Fig. 2, a central, vertical section showing the position of the web-attaching bar when the webbing is under stress;

Fig. 3, a central vertical section showing the position of the web-attaching bar when the webbing is slack and in position to be adjusted, and

Figs. 4 and 5, detail views showing the means for holding the web-attaching bar in its locked position when the buckle is in use.

The buckle generally comprises a frame

but preferably of wire, and a web-attaching bar B slidably mounted on its side members. The frame A comprises a top bar 2, side bars 3, 3 and a lower bar in the form of inwardly projecting pintles 4, 4. The web-attaching bar B consists of the back plate 5, having laterally projecting straps which are curled around the side members 3, 3 to form sleeves 6, 6. Projecting from the lower edge of the back plate 5 is an upwardly projecting lip 7 between which and the back plate is confined the extremity *k* of the webbing C. The lip 7 is pressed down on the extremity *k* of the webbing to permanently grip the same in a manner well known in the art. The other extremity of the webbing is passed forwardly through the opening formed between the web-attaching bar B and the bottom bar 4, 4 and then rearwardly between the web-attaching bar B and the top bar 2, leaving a loop in the webbing depending below the buckle and carrying a cast-off or other suitable connecting piece D. A plurality of web-holding teeth or spurs 8 project from the lower edge of the web-attaching member B being punched out of the metal so as to lie in the same plane with the back plate 5, but having their extremities bent forwardly so that their direction will be substantially at right angles to the path of the webbing passing through the opening under the same when the webbing attaching bar is in its lowermost or locking position, as shown in Fig. 2. The top bar 2 of the frame is preferably provided with a ferrule 10 and the bottom bar 4, 4 with a ferrule 11. These ferrules 10 and 11 serve not only to strengthen the top and bottom bars and enhance the appearance of the buckle but also act as anti-friction rollers to facilitate the passage of the webbing through the buckle when the web-attaching bar is in its unlocked position. The side members 3, 3 of the frame A are provided with snap over lugs 12, 12 on their inside faces adjacent to the lower extremities. These lugs may be formed in any desired manner but are preferably integral with the frame. The web-attaching member B is provided with laterally projecting lugs 13, 13 which are formed on the side edges of its lowermost portion as shown in Figs. 4 and 5. These laterally projecting lugs are of a size and shape and are so positioned that they will snap by the lugs 12, 12 on the

frame when the web-attaching member B is raised and lowered. The sleeves 6, 6 are formed so that they will slide readily upon the side members 3, 3 which have sufficient play therein so that when the projections 12, 12 are engaged by the lugs 13, 13 the side members 3, 3 can spring slightly to permit a snap over action of the lugs the one past the other.

From the above description it will be apparent that when the webbing is under stress the web-attaching member B will be pulled down by the webbing so that it will pinch or grip the portion of the webbing which passes through the opening underneath the same and that the teeth or serrations 8 will materially assist such gripping action. The downward strain on the webbing as it passes over the top edge of the back plate 5 has a tendency to throw the points of the teeth forwardly, thereby causing the same to more securely grip the webbing. Any tendency of the web-attaching member B to slide upwardly out of its locked position should the webbing be momentarily slackened when the buckle is in use is prevented by the lugs 12, 12 on the frame engaging and holding down the lugs 13, 13 on the web-attaching member. This is one of the important features of my invention since in the present style of buckle wherein a sliding bar is utilized to grip the webbing there is not only a tendency for the adjustment of the threaded portion to be disturbed when the strain on the buckle is momentarily relieved, but intermittent stretching of the fabric causes the moving portion to creep perceptibly. When it is desired to lessen the grip on the webbing for adjustment purposes the web-attaching bar B is raised to the position shown in Fig. 3 in which it will be noticed that the teeth 8 have been withdrawn and that the path of the webbing is free and unobstructed through the openings above and below the web-attaching bar. The buckle is preferably constructed so that when the web-attaching bar is in its unlocked position the upper and lower openings would be of the same width as the openings in the buckle should the web-attaching bar be made integral with the frame. That is, the width of the openings above and below the bar would be no greater than necessary to effect a ready adjustment of the webbing when the latter is held in its adjusted position by the friction due to the threading. In making the buckle in this manner and at the same time making the web-attaching bar no wider than is necessary to form lips of sufficient length for gripping the end of the webbing an exceedingly narrow and compact buckle is produced. Of course it is understood that various features of the buckle disclosed are not essential in the

broad idea of my invention since a fairly practical buckle could be produced should the snap over lugs 12 and 13 and the gripping teeth 8 be dispensed with. In such a case the webbing would be locked in its adjusted position by the gripping action alone between the web-attaching bar B and the lower side of the frame. It should be noticed that in the form of my buckle described herein the back of the web-attaching bar is covered with webbing which produces the so called rustless effect. It is conceivable, however, that the webbing may be swaged on the bar in some other manner even though the rustless effect is not preserved. It should be further noticed that the web-attaching bar is the means by which the web is deflected as it passes through the frame thereby eliminating the employment of a separate web-deflecting bar for this purpose. The web-attaching bar also serves as a means for adjusting the width of either the upper or lower opening since it forms the lower side of the upper opening and the upper side of the lower opening. It is apparent that a buckle in which all of the above mentioned features are embodied in the web-attaching bar is economical and efficient and possesses numerous other inherent advantages.

To assemble the device the web-attaching bar B is first swaged onto the end $\frac{1}{4}$ of the webbing C. This operation may be performed either by manually operated tools or automatic machinery in a manner well known in the art and if desired away from the place where the buckle is manufactured. The web-attaching bar is then attached to the frame A of the buckle by curling the straps 6, 6 around the side bars 3, 3 above the lugs 12, 12. The cast-off piece D having been passed on to the webbing the free end is then threaded through the buckle above and below the web-attaching bar B. The web-attaching bar is then pulled down past the retaining lugs 12, 12 and the hose supporter is then ready for use. Thus it would appear that the strain on the webbing is taken up by the web-attaching bar which due to the fact that it is folded on itself to form the lip is not so liable to bend or flex as would be the case if a single thickness of metal only were employed.

While the buckle above described is the preferred form of my invention, yet it is obvious that the same is susceptible to such modification as may fairly come within the scope of the appended claims.

Having now described my invention, what I claim and desire to protect by Letters Patent is:

1. A buckle comprising a frame provided with a webbing opening and a web-deflecting bar slidably mounted on said frame across said opening, in combination with

- a running webbing, one end of which is swaged to said bar, its moving portion being passed forwardly through said opening underneath said bar and rearwardly 5 through said opening over said bar, whereby the said moving portion is deflected by said bar into said opening and the under side of said bar may co-act with the lower side of said opening to grip the webbing 10 when the latter is under stress.
2. A buckle as claimed in Claim 1 wherein the end of the webbing is swaged to the top side of said bar whereby the back of the bar is covered with webbing.
- 15 3. A buckle for running webbing comprising a frame provided with a webbing opening, a web-attaching bar slidably mounted on said frame across said opening and arranged to co-act with the lower side of said opening to lock the running portion 20 of the webbing, and means mounted on said frame for holding said web-attaching bar in its operative locking position.
4. A buckle as claimed in Claim 1 wherein the frame is provided with means for 25 holding the web-deflecting bar against accidental upward movement away from the webbing when the latter is slack.
- In testimony whereof I have hereunto set my hand this 20th day of November, 1918. 30

JOHN ULMER RUSS.
